UNITED STATES PATENT OFFICE.

WILHELM G. DANIELSEN, OF LOGAN, UTAH.

PUSH-RAKE.

SPECIFICATION forming part of Letters Patent No. 658,831, dated October 2, 1900.

Application filed June 19, 1900. Serial No. 20,854. (No model.)

To all whom it may concern:

Be it known that I, WILHELM G. DANIELSEN, a citizen of the United States, residing at Logan, in the county of Cache and State of 5 Utah, have invented a new and useful Push-Rake, of which the following is a specification.

My invention is an improvement in that class of rakes commonly known as "push-rakes," in which the rake-head is arranged 10 in front of the horses and which are used in hay-fields for conveying hay from cocks or windrows to a stack and for other similar purposes.

One object of my invention is to provide a 15 novel push-rake in which the stress of the draft is applied to the elevation of the loaded rake-head from the ground, thereby relieving the driver of the labor of raising the rake-head.

20 A further object of my invention is to provide improved devices for attaching the caster-wheel frame and seat-supporting spring-bar to the rear end of the push-frame.

A further object of my invention is to provide 25 improved means for locking the tilting-bar and rake-head when the latter is loaded and raised.

My invention consists in the peculiar construction and combination of devices herein- 30 after more fully described, and pointed out in the claims.

In the accompanying drawings, Figure 1 is a perspective view of a push-rake embodying 35 my improvements. Fig. 2 is a top plan view of the same. Fig. 3 is a side elevation of the same. Fig. 4 is a detail perspective view showing the rear end of the push-frame, the supporting spring-bar for the driver's seat, a portion of the frame of the caster-wheel, and 40 means for securing the same together. Fig. 5 is a detail sectional view taken on the line *a a* of Fig. 2. Fig. 6 is a similar view taken on the line *b b* of Fig. 2. Fig. 7 is a detail sectional view taken on the line *c c* of Fig. 2.

45 I will first describe the construction of the rake-head. A pair of transversely-disposed bars 1 are bolted on the upper sides at the rear end of the series of rake-teeth 2. Blocks 3 are placed on the upper sides of the bars 1, 50 at the ends thereof, and on the said blocks

are secured, by means of bolts or otherwise, the guard-fingers 4, of which there are two, one on each side of the rake-head and at a suitable distance above the rake-teeth 2, as shown. Blocks 5 are secured on the rake- 55 head, near the rear end thereof, at points about midway between the cross-bars 1. Said blocks are preferably bolted to appropriate rake-teeth, but may be otherwise secured, and on the said blocks are bearings 6, in 60 which is secured an axle-shaft 7, provided with supporting-wheels 8. The length of the axle-shaft is less than the width of the rake-head, and said supporting-wheels are disposed within the sides of the rake-head, as 65 shown. A transversely-disposed bar 9 is secured to a series of supporting inclined brace-bars 10, which rise from the cross-bars 1 and the rear portions of the guard-fingers 4, the said bar 9 and brace-bars 10 forming a lever 70 which projects from the upper side of the rake-head, at the rear end thereof.

The push-frame extends rearward from the rake-head and comprises a pair of push-bars 11, the front ends of which are provided with 75 pivotal bearings 12, which turn on the axle-shaft 7, and thereby the rake-head is pivotally connected to the front end of the push-frame, so that by tilting said rake-head rearwardly the rake-teeth may be raised from the 80 ground. A cross-bar 13 extends transversely across and projects beyond the push-bars 11 and is secured thereto by bolts, as at 14. A draft-beam 15, near the rear end of the push-frame, is disposed transversely across the 85 push-bars 11 and secured thereto by means of clip-bolts 16 or in any other suitable manner. A pair of plates 17 18 are bolted to the upper and lower sides of the push-bars 11, at the rear ends of the latter. Central openings 19 are made in said plates and form bearings for the vertical spindle or rudder-post 20 of the caster-frame 21, in which is mounted a trailing caster-wheel 22. The plate 18 is provided on its upper side with transversely- 90 disposed ribs or flanges 23, having notches 24 on their upper sides, which form seats for the front lower end of the spring-bar 25, which serves to support the seat 26 for the driver. The heel of the said spring-bar bears 100

upon the upper end of the spindle or rudder-post 20 of the caster-frame. A plate 27 is disposed transversely on the heel of the said spring-bar and is secured thereon by means of 5 clamp-bolts 28, which pass downward through the plates 18 17. A pair of brace-bars 29 are bolted on the plate 18 and to the end portions of the draft-beam 15.

I will now describe my improved means 10 whereby the stress of the draft exerted by the team is utilized in the tilting or elevation of the rake-head when the latter is loaded. A plate 30 is bolted on the upper side of the draft-beam 15 at an appropriate point, preferably to one side of the center thereof, as 15 shown, and is provided with a bearing 31, to which is pivoted the lower end of a hand-lever 32. Said hand-lever is provided at a suitable distance from its lower end with a foot- 20 step 33. A tilting-bar 34 is provided at its front end with a pair of forward-extending plates 35, bolted thereto, and pivotally connected to the bar 9 of the rake-head by a bolt 36. The said tilting-bar is provided at its 25 rear end with rearward-extending plates 37, which are bolted on opposite sides thereof, as at 38, said plates extending rearward from said tilting-bar and forming a bifurcated extension thereof and passing on opposite sides 30 of the hand-lever 32, to which they are pivotally attached by a bolt, as at 39. It will be observed by reference to the drawings, more particularly by reference to Fig. 5 thereof, that the pivotal bolt 40 at the lower end of 35 the hand-lever 32 is at some distance above the plate 30 and that when the hand-lever 32 is turned rearward to its full extent to draw the tilting-bar rearward, and thereby lift the teeth of the rake-head from the ground, the 40 pivotal connection 39 between the tilting-bar and the hand-lever passes slightly below the dead-center, the hand-lever being stopped by contacting with the upper side of the plate 30, and thereby said hand-lever is locked in position to maintain the loaded rake-head with 45 its teeth in their elevated position.

A pair of draft-levers 41 are disposed on the end of the draft-beam 15 and pivotally connected thereto, as at 42, by the means 50 usually employed for pivoting a doubletree. The outer ends of the said draft-levers project beyond the ends of the said draft-beam and are provided with singletrees 43, attached thereto in the usual manner. The inner ends of said draft-levers are connected, by means of rods or chains 44, to an equalizing-bar 45, which is pivoted to the tilting-bar 34 at an appropriate point by means of a bolt 46. It will be understood that the draft-bars 55 being thus connected together and to the tilting-bar equalize the draft between the horses, and, moreover, that by this arrangement of the draft-levers and the tilting-bar the stress of the draft when the team is started, as the 60 rake-head is lowered so as to run its teeth

under a pile of hay, as a hay-cock or a windrow, to load the rake-head, is applied to the tilting-bar to move the latter rearwardly, thereby tilting the rake-head on its axle and serving to elevate the load. The lever is operated by hand by the driver to facilitate the raising of the loaded rake-head, if required; but all or practically all of the power required to tilt and raise the loaded rake-head is furnished by the team and the driver is relieved of laborious operation of the lever. Swing-rods 47 are pivotally secured to the ends of the cross-bar 13 and are provided at their outer ends with links 48, to which the collars of the team are attached in a suitable 75 manner.

It will be understood that the push-rake, being provided at the rear end of its push-frame with the pivoted trail or caster frame and supporting-wheel 22, mounted therein, the 80 push-rake may be driven in any required direction and readily turned by the team.

Having thus described my invention, I claim—

1. In a push-rake, the combination of a pivotally-supported rake-head, a push-frame, a hand-lever pivoted at its lower end at a point above the upper side of said push-frame, a tilting-bar connected to the rake-head and attached to the hand-lever at a point above the pivot of the latter, whereby said hand-lever may be swung rearward, past the dead-center, when the rake-teeth are elevated by the tilting of said rake-head, and thereby lock the same in an elevated position, draft-levers 90 on the push-frame, and connections between said draft-levers and said tilting-bar, substantially as described.

2. In a push-rake, the combination of a pivotally-supported rake-head, a push-frame, a hand-lever pivoted to said push-frame, a tilting-bar having its front end flexibly connected to the rake-head and its rear end connected to said hand-lever, draft-levers on the push-frame, an equalizing-bar pivoted to the tilting-bar and connections between said equalizing-bar and said draft-bars, substantially as described.

3. In a push-rake, the combination with the push-bar, of the connecting-plates therefor, on the upper and lower sides thereof, the upper connecting-plate having ribs or flanges on its upper side, the seat-supporting bar having its foot seated in said ribs or flanges and secured on said upper plate, and the caster-frame having the spindle or rudder-post in bearings in said plates, and bearing under the foot of the seat-supporting bar, substantially as described.

4. In a push-rake, the combination with the push-bars, of the connecting-plates therefor, on the upper and lower sides thereof, the upper connecting-plate having ribs or flanges on its upper side, the seat-supporting bar having its foot seated in said ribs or flanges, a

plate disposed on the upper side of the foot of said seat-supporting bar, and clamping-bolts passing through said plate, said connecting-plates and said push-bars, and the 5 caster-frame having its post journaled in bearings in said connecting-plates, substantially as described.

In testimony that I claim the foregoing as my own I have hereto affixed my signature in the presence of two witnesses.

WILHELM G. DANIELSEN.
